UNITED STATES PATENT OFFICE.

LOUIS ROBINSON, OF MONTREAL, QUEBEC, CANADA.

DESIGN FOR A DETACHABLE COLLAR.

SPECIFICATION forming part of Design No. 17,188, dated March 15, 1887.

Application filed December 31, 1886. Serial No. 223,158. Term of patent 7 years. Patented in Canada December 22, 1886.
Design No. 4.

To all whom it may concern:

Be it known that I, LOUIS ROBINSON, residing at the city of Montreal, in the District of Montreal and Province of Quebec, Canada, 5 have invented and produced a new and original Design for Detachable Collars, of which the following is a specification, reference being had to the accompanying drawing, forming part thereof, and showing a plan view of 10 such collar.

The design consists of an upper flap or collar proper, A, having its inside edge, *a*, circular and its outside edge curved back from the meeting-points at the front to its full width, 15 and then corresponding in outline with the inside, save that a very blunt apex is formed upon it at the extreme rear. The part lettered B has its inner edge partly conforming to the edge *a*, being at the front points of the collar

proper, A, sloped outward, so as to form projecting lappets with parallel sides and rounded ends, the outer edge under the flap A forming a curved line and the width of the band B lessening to a blunt apex formed in the rear. 20

What I claim is as follows:

The design for a detachable collar herein shown and described, consisting of the upper collar round on the inside, outside edge rounded back from front meeting-points to full width, corresponding in outline to the inside, and the under flap, also round on the inside, with projecting lappets having rounded ends, and its outer edge curved. 25 30

LOUIS ROBINSON.
